UNITED STATES PATENT OFFICE.

CHARLES F. SMITH, OF NEW YORK, N. Y.

MAIL-BAG EXCHANGE.

1,393,980.

Specification of Letters Patent.

Patented Oct. 18, 1921.

Application filed September 12, 1918, Serial No. 253,765. Renewed March 12, 1921. Serial No. 451,843.

To all whom it may concern:

Be it known that I, CHARLES F. SMITH, a citizen of the United States, residing at New York, in the county of New York and State of New York, have invented certain new and useful Improvements in Mail-Bag Exchanges, of which the following is a specification.

This invention relates to railway mail delivery, and more especially to a combined receiver and support; and the object of the same is to produce an improved device for delivering a bag from a car to a station and at the same time picking up a bag at the station by a receiver on the car—thus effecting an exchange of mail bags without interrupting the progress of the train.

Another object of the invention is to produce a support at the station which may be turned aside out of the way and a support on the car which may be turned on its pivots so that the door can be shut.

Other objects will appear in the following specification of details, reference being had to the drawings, wherein:

Figure 1 is a side elevation of the post alongside the track at the station and a section through the mail car,

Fig. 2 is a plan view, being a horizontal section through the doorway of the mail car,

Fig. 3 is an enlarged detail in side elevation of one of the snap rings,

Fig. 4 is a detail of the tongue on the finger for holding said rings.

At or near each station there is erected a base 1 having in its upper end a socket 2 in which is stepped for rotation a pin 3 at the lower end of an upright post 4, and fast on said post just above the top of the base is a ring from which projects a handle 6 movable in a horizontal plane over a plate 7 fastened on the top of the post and having holes 8. The post may also be provided with a yoke as seen at 9. Through the handle and possibly also through the yoke is dropped a pin 10 adapted to engage one of the holes 8, and the pin is held against loss by means of a small chain 11. When this pin engages what might be called the rear hole in the top plate 7, the parts stand in active position as seen in Fig. 2. At other times the handle is swung around to a position parallel with the rails 12 and the parts are in inactive position, the pin being

dropped into one of the other holes 8 which are exposed in Fig. 2.

Secured to the post 4 in any suitable way, as by collars 15 and set screws 16, are the inner ends of arms 17 and 18 which constitute one pair having at their outer ends fingers projecting away from the reader in Fig. 1 and therefore not shown. Also in the same manner there are mounted on the post two other arms 19 and 20 constituting another pair standing respectively above the first-named arms and having at their outer ends fingers 21 and 22 projecting toward the reader in Fig. 1. The fingers of what might be called the lower pair of arms in Fig. 1 are therein shown as supporting rings 23 and 24 which are respectively and removably connected with opposite ends of a mail bag lettered A standing upright between and supported by arms. The ring is shown at 24 in Fig. 3 as considerably enlarged, its upper side flattened a little as at 25 and overlying the finger 26, being held thereon by means of a spring tongue 27 so that it may not become accidentally dislodged. The ring is split or cut away at one side, and the opening thus produced is closed by a spring tongue 28 so that the entire device becomes what might be called a snap ring, much like a snap hook and serving substantially the same function. The two rings 23 and 24 are properly spaced to engage the fingers of any pair of arms and they might be slipped onto or slipped off of the same and under the retaining tongues 27 by hand and with ease; but when they are to be disengaged from the rings or other devices on the mail bags, the tongues 27 must be sprung to permit it. The bag A shown in Fig. 1 is carried by the post 4 and is to be taken by the catcher on the passing car. The bag B in the same view is carried by the car and is to be left on the fingers of the other pair of arms 19 and 20. The upper end of the bag B is broken away for greater clearness, but it is provided with a pair of rings like that numbered 24 as best seen in Fig. 3.

In the side bars of the door opening 30 of the car 31 are mounted upright keepers 32 having notches 33 closed at their lower ends and opened at their upper ends as best seen in Fig. 1, and removably fitting in each notch is a square head 34 at one end of a cross bar 35 which extends across the door opening and is provided at its center

with an offset or crank 36 projecting beyond the side wall of the car and affording a bearing for the element yet to be described. Rotatably mounted on the uppermost crank is an eye 37 formed at the juncture between a lever 38 and a pair of fork arms 39 and 40, the uppermost arm 39 having a finger 41 projecting toward the reader above the finger 21 as seen in Fig. 1, and the lowermost fork arm 40 having a finger projecting from the reader in the same view and therefore not visible. A duplicate of this structure is mounted on the lowermost crank, and its details need not be recited. On the intermediate crank 46 is mounted an eye 47 at the outer end of a hand lever 48 which projects into the car. A link 45 pivotally connects the two levers 38 and the hand lever 48, and a pin 44 is provided for engaging holes 43 in the hand lever and link when they register. I may here say that when the parts stand in the position shown in this view, the outer ends of the upper fork arms 39 and their fingers 41 travel just above the outer ends of the upper arms 19 and 20 and their fingers 21 and 22; whereas the outer ends of the other fork arms 40 and their fingers travel just beneath the outer ends and fingers of the other pair of fork arms 17 and 18 on the post. It is the fingers of the last-named arms which will pass through the rings 23 and 24 and pick up the bag A as the car passes the station whereas the fingers 41 on what might be called the upper pair of fork arms support the bag B which has been hung outside the car door and this bag is delivered onto the fingers 21 and 22 of the upper pair of arms on the post and left at the station. Therefore the exchange of bags is entirely automatic and needs no attention on the part of operators either at the station or in the car.

When the device at the station is not in use, the pin 10 is lifted and the entire structure turned aside because the pin 3 at the lower end of the post rotates within the socket 2 in the base 1; and now the trains may pass to and fro and all parts of the station structure are out of the way. When the structure on the car is not to be used, the hand lever 48 is borne downward and the link 45 causes the other two levers 38 to swing downward simultaneously. This throws the fork arms upward so that the arms numbered 39 come into the door opening 30 and the arms numbered 40 and their fingers rise to a position above the cranks 36 in the bars 35. The hand-hold on the hand lever 48 now passes into the door way 30, and a sliding door (see fragmentary section marked D in Fig. 1) may be moved across the door opening to close the same, leaving all parts of the car structure outside the door. When the structure is not

desired at all for use during a trip, the heads 32 and the cross bars 35 may be lifted out of the notches 33 and the whole device carried into the car; but whether its fork arms are swung upward or it is bodily moved, no part of this structure projects any great distance beyond the outside of the car to strike anything alongside the track. When the car structure is brought into use, it is desirable that the parts stand as seen in Fig. 1, and for this purpose I have provided stops 50 on the eyes which automatically engage the cranks and hold the several elements as shown.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a mail bag handling device, the combination with keepers adapted to be attached to the sides of the door opening in a mail car, three cross bars, and adjustable connections between their extremities and the receptive pairs of keepers, the mid-lengths of said cross bars being offset; of mail bag supports rotatably mounted on the upper and lower bars and having levers at their inner ends, a hand lever mounted on the intermediate bar, and link connections between all said levers.

2. In a mail bag handling device, the combination with a keeper adapted to be attached to one side of the door opening in a mail car and having a notch open at its upper end; of a bar having at one extremity a square head removably insertible in said notch, the bar having its body offset out of line with the car wall, a mail bag support having an eye mounted on said offset portion, and means for manually adjusting its position thereon.

3. In a mail bag handling device, the combination with keepers adapted to be attached to the sides of the door opening in a mail car and having notches open at their upper ends; of a cross bar within the door opening having square heads at its ends for engagement with said notches and an offset crank at its center standing outside the line of the car wall, a mail bag support having an eye rotatably mounted on said crank and a lever standing within the door opening, and means for manually adjusting the position of said lever.

4. In a mail bag handling device, the combination with keepers adapted to be mounted in the sides of a car door opening, and a

plurality of cross bars having headed extremities removably engaging said keepers; of swinging mail bag supports mounted on the upper and lower bars, a hand lever 5 mounted on the intermediate bar, and a link pivotally connecting said supports and hand lever, for the purpose set forth.

5. In a mail bag handling device, the combination with keepers adapted to be mounted in the sides of a car door opening, and a 10 plurality of cross bars removably engaging said keepers and offset between their ends into cranks standing outside the line of the

car wall; of mail bag supports mounted on the uppermost and lowermost cranks and 15 each comprising a forked outer end and a lever at its inner end, a hand lever having an eye mounted on the crank of the intermediate cross bar and adapted to project into the car when said forks project outside 20 of the car, and a link connecting the three levers whereby said hand lever may be moved to throw the forks out of active position.

In testimony whereof I affix my signature. 25
CHARLES F. SMITH.
